UNITED STATES PATENT OFFICE.

WILLIAM H. KELLY, OF NEW YORK, N. Y.

LAWN-POOL APPARATUS.

SPECIFICATION forming part of Letters Patent No. 278,341, dated May 29, 1883.

Application filed April 14, 1883. (No model.)

To all whom it may concern:

Be it known that I, WILLIAM H. KELLY, a citizen of the United States, residing at New York, in the county of New York and State of New York, have invented certain new and useful Improvements in Lawn-Pool Apparatus; and I do hereby declare the following to be a full, clear, and exact description of the invention, such as will enable others skilled in the art to 10 which it appertains to make and use the same, reference being had to the accompanying drawings, and to the letters or figures of reference marked thereon, which form a part of this specification.

15 My invention relates to games; and it consists in the construction and arrangement of wickets of different sizes, around which is made to pass in a novel manner a belt or strip of leather, canvas, rubber, or other suitable material, 20 thereby forming pockets and cushions, which, in combination with mallets—such as those used in the game of "croquet"—and a sufficient number of balls made of wood, rubber, or other resilient material, form an apparatus 25 with which a game similar to that known as "fifteen-ball pool" can be played upon the lawn or on the floor of a room.

In the drawings, Figure 1 is a perspective view of my improved "ground-pool" apparatus, 30 showing the balls scattered on the ground or floor after a "burst." Fig. 2 is an enlarged perspective view of a portion of the improved apparatus by which is formed a "pocket." Fig. 3 is a front elevation of a portion of one 35 of the wickets, showing the method of attaching the wickets to the floor. Fig. 4 is a perspective view of one of the wickets forming the pocket. Fig. 5 is a vertical transverse section cut through one of the pockets, and 40 Fig. 6 is a detailed view of an end of one of the wickets constructed to be fastened directly to the floor.

Wickets B, of staple form and of comparatively small span, are stuck in the ground or 45 fastened to the floor of a room, and occupy positions in relation to each other corresponding to those occupied by the "jaws" or pockets found upon the well-known fifteen-ball-pool table. Wickets C, of a larger span, are located 50 outside of wickets B in such a manner as to form a frame-work for the back of the pockets D. A light outwardly-swinging gate, E, is

swung from the top of the wicket B, and is prevented from swinging inwardly by the cross-piece e, rigidly attached to the wicket. 55 This gate prevents the ball from bounding out of the pocket after having once passed therein, as shown in Fig. 5. One end of a leather, canvas, or other strip, A, is passed under or inside of the inner or smaller wicket, B, then 60 around or outside of larger or outer wicket, C, then back through or inside of wicket B, thus forming a pocket, D, as shown in Fig. 2. The strip end is then carried to the next adjacent wickets B and C, and passed under and 65 around them, respectively, in the manner above described, this being repeated until the six pockets and side rails are formed, as shown in Fig. 1, the continuous strip forming the cushions or rails. The two ends of the strip may 70 then be connected by strings, buckles, or other equivalent device, or one end may be secured to a leg of one of the wickets and the other made fast to a drum, as shown in dotted lines at D' in Fig. 1. By this method of fastening, 75 all looseness may at any time be taken up and the belt made taut.

When the ground-pool is to be played indoors, sockets E', screwed or otherwise fastened to the floor, form seats for the reception of the 80 ends of the wickets, as shown in Fig. 3. The wickets may be screwed or otherwise fastened directly to the floor without the interposition of sockets, as shown in Fig. 4. The balls a 85 may be plain or may be numbered from one to fifteen, and vary in color in the usual well-known way. The object-ball a', driven by the mallet b in the hand of the player, is made to strike any one of the fifteen balls a in such a 90 manner as to drive them into any one of the 95 pockets.

It is obvious that any number of pockets, or any number of balls, or any variation of the rules regulating the game of fifteen-ball pool may be used without changing the nature of 95 my invention.

I am aware that wickets have heretofore been used through which balls have been made to pass, and that guiding or bounding rails have also been used in short sections. These 100 I do not broadly claim; but

What I do claim, and desire to secure by Letters Patent, is—

1. The wickets B and C, in combination

with a continuous belt or strip, A, for the purposes of a game.

2. The ground-pool pocket D, formed by the passage of the end of a continuous strip, A, 5 under the wicket B, around or outside of wicket C, and back under wicket B, substantially as described.

3. In combination with wickets B and C and cushion-strip A, the strip-tightening mechanism D', substantially as described.

4. In combination with strip A and wickets B and C, the sockets E', whereby the apparatus may be attached to the floor of a room, in the manner described.

5. The apparatus for playing the game of ground-pool, the material parts of which consist in the wickets B and C, strip A, balls a, object-ball a', and mallet b, substantially as a. 1 for the purposes set forth.

6. The combination with wickets B and C 20 and cushion-strip A, the outwardly-swinging gate E, substantially as described.

In testimony whereof I affix my signature in presence of two witnesses.

WM. H. KELLY.
